UNITED STATES PATENT OFFICE.

MARTIN H. SCHIRMER AND JOSEPH LEHR, OF ROCHESTER, NEW YORK.

PRESSING-MACHINE.

946,401.

Specification of Letters Patent. Patented Jan. 11, 1910.

Application filed October 7, 1905. Serial No. 281,748.

To all whom it may concern:

Be it known that we, MARTIN H. SCHIRMER and JOSEPH LEHR, both of Rochester, in the county of Monroe and State of New York, have invented certain new and useful Improvements in Pressing-Machines; and we do hereby declare the following to be a full, clear, and exact description of the same, reference being had to the accompanying drawings, forming a part of this specification, and to the reference-numerals marked thereon.

Our present invention relates to improvements in pressing machines and more particularly to that type adapted for pressing and smoothing the seams and creases in garments, and the purpose of our present invention is to provide such a machine with improved mechanism for producing the necessary pressure upon the garments arranged between the iron and the pressing surface whereby ample pressure may be applied to the garment with a machine of small dimensions, and also to provide improved controlling devices whereby the pressure mechanism may be conveniently and accurately controlled by the operator.

To these and other ends the invention consists of certain improvements and combinations of parts all as will be hereinafter more fully explained, the novel features being pointed out in the claims at the end of the specification.

In the drawing: Figure 1 is an elevation of the pressing machine constructed in accordance with our invention, parts being shown in section; Fig. 2 is a view similar to Fig. 1 showing the operating parts in the positions they would occupy during the pressing operation; Fig. 3 is a plan view of the pressing machine; Fig. 4 is a detail view of the operating handle and the controlling devices adjacent thereto, and Fig. 5 represents a section on the line 5—5 of Fig. 4.

Similar reference numerals in the several figures indicate similar parts.

A pressing machine constructed in accordance with our invention comprises generally a rigid support 1 having a vertical bearing 2 thereon to receive the corresponding bearing member of a horizontally-swinging, supporting-arm 3, the free end of the latter being provided with a bearing 4 to receive the bracket 5 of a horizontally-movable frame 6, the latter being preferably yoke-shaped to provide the spaced parallel arms 7 and 8, the

supporting arm 3 and the frame 6 forming a jointed or articulated arm. Passing through the free ends of the arms 7 and 8 is a bearing pin 9 on which is pivoted a rocker arm or lever 10. On one end of this rocker arm is mounted a suitable operating motor, embodying in the present instance a fluid pressure cylinder 11 having a piston 12 fitted to operate therein and provided with a piston rod 13 arranged to operate through a guide 14, the free end of this piston rod being pivotally connected at 13^a to one end of a bell-crank lever 15, the latter being pivoted at 16 so as to swing on the brackets 17 of 70 the yoke frame 6, the other end of this bell-crank lever being pivotally connected at 18 to the link 19, the latter in turn being pivotally attached at 20 to the under side of the rocker arm 10. The cylinder relation and 75 length of the arms of the bell-crank lever 15 and of the link 19 are such relatively to the bearing centers 16, 18 and 20 respectively, that as the piston rod 13 is forced out of the cylinder as the latter swings in an 80 arc about the pivot 9 of the rocker arm, the bell-crank lever 15 and the link 19 which form an operative connection between the piston, the yoke frame and the rocker arm, will maintain the pivot 13^a of the piston in 85 alignment with the changing axis of the cylinder as the latter swings with the rocker arm, thereby obviating the necessity of using a cross head and guides for the piston.

It is preferable to employ a suitable re- 90 tracting device for the motor and rocker arm; and in the present instance such a device is supplied by providing the bell-crank lever 15 with an arm 21 having a hook or projection 22 thereon, and with this hook is 95 arranged to cooperate a yoke-shaped rod 23, the arms of the latter passing through apertures in a horizontal pin 24 which is mounted to rotate in a bearing on the rocker arm 10, and between this pin and the end of the 100 arms are interposed the compression springs 25. These springs normally operate to draw the looped portion of the rod toward the pin 24, and as this portion is normally attached to the hook 22 of the bell-crank lever, they 105 will operate to draw the bell-crank lever into the position shown in Fig. 1, thereby returning the piston within the cylinder and restoring the rocker arm to its normal horizontal position.

The forward end of the rocker arm 10 is provided with a spherical bearing 26 to re-

ceive and center a spherical journal portion 27 formed on a vertically-arranged shaft 28, the lower end of the latter being attached to an iron 29, and the latter is arranged to 5 move into and out of coöperative relation with a table or pressing surface 30 by the relative angular motion of the rocker arm. The upper end of this iron-supporting shaft 28 has a handle 31 attached thereto by means 10 of which the iron attached thereto may be guided and manipulated, and extending laterally from the upper end of this shaft is an arm 32 having a substantially U-shaped actuating lever 33 pivoted thereto at 34, a link 15 35 being attached to this lever at 36 and connected at 37 to an operating member or lever 38, the latter being pivoted at 39 and provided at its free end with an operating handle 40, conveniently located relatively to the 20 handle 31, to enable it to be operated by the operator's thumb while grasping the iron handle, (see Fig. 4). If desired, a suitable device may be provided for retaining this operating lever in operated position, such a 25 device comprising in the present instance, a latch 41 pivoted to a suitable bracket 42, the said latch being provided with a notch 43 adapted to receive a portion of the operating lever 38 when the latter has been moved into 30 operated position, the latch 41 moving into the position shown in dotted lines in Fig. 5. The free end of the lever 33 is provided with a roller 44 arranged to coöperate with a spherical bearing 45 on one arm of a bell- 35 crank lever 46, the latter being pivoted at 47 to the rocker arm 10 and provided with a counterweight 48 which normally operates to elevate the spherical bearing 45. The vertical arm 49 of this bell-crank lever is pivotally connected at 50 to a rod 51, the latter being pivotally attached at 52 to a pivoted finger 53, which in turn is pivoted at 54 to an extension on the fitting 55, and operating longitudinally in this fitting is a plunger 56 40 having a valve seat 57 at one end and a roller 58 at its opposite end arranged to coöperate with the free end of the finger 53.

Secured to the cylinder 11 is a valve casting 59 to one end of which the fitting 55 is 50 connected by the nut 60 secured upon the threaded extension 61, a gland 62 being formed to provide a stuffing box. This casting is provided with an annular chamber 63 and a passage 64 leading from this chamber 55 to the interior of the cylinder above the piston head 12, and extending through the chamber 63 of the casing is a valve stem 65 one end of which passes through the stuffing box and nut 60 to coöperate with 60 the valve seat 57 on the plunger 56. This stem is provided with an axial bore 66 which has an exhaust at one end controlled by the valve seat 57, and a portion of the stem within the chamber 63 is provided with a 65 groove or passage 67 which forms communica-

cation between the bore of the stem and the annular chamber of the casing. This stem passes through a valve seat 68 in the casing, the valve stem being provided with a valve 69 to coöperate with this seat and an extension 70 for guiding the stem. A pipe 71 is attached to the valve casing beyond the valve and connected to a suitable source of fluid pressure supply, fluid pressure therefrom being admitted to the cylinder under 75 the control of the valve.

In operating a machine of this kind for the purpose of smoothing and pressing garments, and for similar purposes, the parts to be pressed are properly arranged on the 80 stationary table 30, and the required pressure is imposed upon the iron 29 by rotating the operating lever 38 toward the left (see Fig. 4), and this lever through the link 35 and its connection 36 will tilt the lever 33 85 forwardly about its pivot 34, causing the roller 44 on its lower end to bear down onto the spherical bearing 45 on the forward arm of the bell-crank lever 46, causing the latter to be operated into the position shown in 90 Fig. 2. If desired, this manually-operated lever 38 may be locked in operated position to sustain a constant pressure between the iron and pressing surface by swinging the detent 41 into the position shown in dotted 95 lines in Fig. 5, causing the operating lever to be locked in the recess 43 thereon. By moving the bell-crank lever into the position shown in Fig. 2, the arm 49 thereon operating through the rod 51 will cause the 100 pivoted finger 53 to operate the plunger 56, moving the valve seat 57 thereon rearwardly against the valve stem 65, closing the exhaust end of the bore 66 thereof and also moving the stem rearwardly to unseat the 105 valve 69 from its seat 68. This will admit fluid pressure from pipe 71 to the chamber 63 of the valve casing, passing between the valve seat 68 and valve 69 and through the longitudinal groove or opening 67 in the 110 valve stem, and from the chamber 63 it passes through the passage 64 into the cylinder 11 between the head thereof and the piston 12. The fluid pressure operating on the piston and cylinder heads will tend to 115 separate them in opposite directions, the piston rod 13 operating on the bell-crank lever 15 to rotate it about its pivot 16 on the frame 6 as a fulcrum, and causing an upward movement of the link 19 attached 120 thereto at 18, the force thus exerted by the link 19 operating on the rocker arm 10 to tilt it, the forward end thereof carrying the iron 29 moving downwardly toward the stationary table or pressing surface 30. At 125 the same time the fluid pressure operates on the cylinder head which will tend to lift the cylinder, and with it, the rear end of the rocker arm, thereby utilizing the full stroke of the cylinder and thus supplement- 130

ing the force of the piston in depressing the forward end of the rocker arm. This will bring the iron 29 down upon the pressing surface 30 or on the garment or other parts thereon to be smoothed or pressed, with a pressure which may be maintained constant if desired by engaging the detent 41 with the manually-operated lever 38, or if desired, the amount of pressure applied to the garment may be varied during the pressing operation by varying the pressure of the thumb upon the handle 40 of the operating lever 38 by the thumb of the operator, the hand grasping the handle 31 to guide and manipulate the iron 29.

The jointed supporting arm permits the iron and its connected parts to be moved freely in a horizontal plane to any part of the stationary table 30 without varying the pressure applied between the iron and pressing surface, as the pressing surface of the table is arranged in a plane parallel to the plane of movement of the arm 3, and the rocker arm carried thereby. When the bell-crank lever 46 is in operated position, as shown in Fig. 2, the roller 44 of the lever 33 bearing on the spherical surface 45 will remain motionless, while the iron 29 and its shaft are rotated or given a relative rocking motion about the universal bearing 26 and 27 of the rocker arm 10, as the surface of this spherical bearing is concentric with the center of motion of the shaft 28 carrying the iron when the bell-crank lever 46 is in operated position, and therefore the various motions given to the iron and the rocker arm 10 will not disturb the connections of the controlling mechanism nor affect the pressure which is under the control of the manually-operated lever 38, the relative positions of the operating lever and the bell-crank lever 46 which controls the fluid pressure supply remaining unchanged during the various relative angular and rotary motions of the iron and rocker arm by means of this connection between them.

The pressure upon the iron 29 may be removed and the parts restored to normal position to lift the iron from the table 30 by returning the manually-operated lever 38 to normal position, allowing the lever 33 to be lifted by the rising of the spherical bearing 45 under the action of the counter-weight 48 of the bell-crank lever 46, causing the latter to be returned to normal position and thus withdraw the finger 53 from engagement with the plunger 56, to permit the exhaust valve seat 57 to be moved outwardly by the valve stem 65 consequently uncovering the exhaust end of the bore 66 thereof, and also allowing the valve 69 to coöperate with its seat 68, thereby cutting off the fluid pressure supply to the cylinder. As the bore 66 of the valve stem communicates through the slot 67 with the chamber 63 and the

latter in turn communicates through the passage 64 with the space between the piston and cylinder heads, the fluid pressure confined within the cylinder will exhaust into the atmosphere, and as the springs 25 operate through the yoke 23, and the arm 21 of the bell-crank lever 15, to return the latter to normal position, the piston will be returned within the cylinder and the rocker arm 10 will be brought into a horizontal position lifting the iron from the table.

Sometimes it is desirable to apply the iron to the garment with a moderate pressure which may be produced manually by the operator, and in this case the spring-actuated retracting mechanism may be thrown into inoperative position by drawing the handle 72 forwardly, rocking the lever 73 and causing the rod 74 to be moved rearwardly, and as this rod is connected to the yoke 23 of the retracting device, it will disengage the latter from the hook 22 on the bell-crank lever 15, and thereby release the tension operating to return the rocker arm 10 to the normal horizontal position. When these parts have been disengaged, the rocker arm 10 may be freely tilted without resistance, and the operator by pressing upon the handle 31 may subject the garment to the desired pressure and the iron may be manipulated or directed in any desired course as described in connection with the fluid pressure mechanism.

A pressing machine embodying our invention is not only capable of producing a comparatively heavy pressure on the garments or other articles being pressed, but the machine is compact in dimensions so that it may be readily and easily handled by the operator, the manner of mounting and connecting the motor enabling the full stroke of the cylinder to be utilized while the rocker arm swings through a comparatively small angle, the cylinder being attached directly to the rocker arm while the piston is connected thereto through the lever 15 which has a bearing on a portion of the relatively stationary frame as a fulcrum. Furthermore the motor connections are shortened and simplified by avoiding the use of the customary guides and crosshead, the pivot 13^a of the piston attached to the bell-crank lever 15 swinging in a given arc at a speed timed according to the motion of the rocker arm by means of the link 19, so that the pivot 13^a of the piston rod will be maintained in alignment with the cylinder axis while the rocker arm swings with the cylinder about the pivot 9. The novel controlling mechanism for the motor also enables the motor to be readily and accurately controlled by the same hand of the operator which is employed in directing the course of the pressing iron, and the connecting devices are such that the variations in angular relation of the iron and

rocker arm does not affect the motor control. Moreover, it is advantageous to arrange the motor on the rear end of the rocker arm as it counterbalances the pressing iron and is sufficiently removed therefrom to enable leather or other soft packing to be employed in the cylinder without drying it out by reason of the heat from the iron, and as the weight of the motor is so far removed from the iron, its inertia does not materially affect the ease of manipulation of the iron on the pressing surface as is true of those devices having the iron attached directly to the piston of a motor.

15 We claim as our invention:

1. In a pressing machine, the combination with a pressing surface, of a jointed arm arranged to swing in a plane parallel to the pressing surface, a rocker arm carried by the jointed arm and mounted to swing angularly to the pressing surface, an iron carried by the rocker arm, and a motor operating on the rocker arm and arranged between it and the jointed arm to produce pressure between the iron and pressing surface.

2. In a pressing machine, the combination with a horizontal pressing surface, of a pivoted arm arranged to swing freely in a horizontal plane, an intermediately-pivoted rocker arm carried by the first arm and arranged to swing in a vertical plane, an iron carried on one end of the rocker arm and a motor operating on the other end thereof to produce pressure between the iron and pressing surface.

3. In a pressing machine, the combination with a pressing surface, a pivoted arm arranged over said surface and a rocker arm journaled at a point intermediate its ends to the pivoted arm and arranged to swing in a plane intersecting the plane of movement of the pivoted arm, of a motor arranged between the latter and the rocker arm at one side of the pivoted point of the latter for tilting the rocker arm relatively to the pressing surface and an iron attached to the rocker arm.

4. In a pressing machine, the combination with a pressing surface, of a jointed arm arranged to swing in a plane parallel to the pressing surface, a rocker arm carried by the first-mentioned arm and arranged to swing angularly to the pressing surface, an iron carried by the rocker arm, and a motor arranged between the said arms for producing pressure between the iron and the pressing surface.

5. In a pressing machine, the combination with a pressing surface, of a jointed arm arranged to swing in a horizontal plane, a rocker arm carried by the first-mentioned arm and pivoted intermediately to swing in a vertical plane, an iron carried on one end of the rocker arm having an operating handle for guiding it over the pressing surface,

a motor carried at the other end of the rocker arm for moving the iron toward the pressing surface, and controlling devices connected to the motor and having an operating member adjacent to the iron-operating handle.

6. In a pressing machine, the combination with a suitable pressing surface, of an arm mounted to swing in angular relation to the pressure surface, an iron having a supporting shaft mounted in a universal bearing on said arm, a motor mounted separately from said shaft for operating said arm to move the iron into co-operative relation with the pressing surface, and controlling devices connected to the motor and having an operating member on the supporting shaft of the iron.

7. In a pressing machine, the combination with a pressing surface, of an arm mounted to swing in angular relation to the pressure surface, an iron having a shaft connected by a universal bearing with the arm, a motor carried by said arm for moving the iron into co-operative relation with the pressing surface, and controlling devices for the motor embodying an operating member on the said shaft, and devices for maintaining operative connection between the operating member and motor irrespective of the different angular relations of the said arm and shaft.

8. In a pressing machine, the combination with a suitable pressing surface, of an arm mounted to move in angular relation to the pressing surface, an iron having a supporting shaft connected by a universal bearing to said arm, a motor mounted separately from the said shaft and devices for controlling it embodying a lever supported on the arm having a bearing surface formed concentric with the shaft-bearing, a part co-operating with the bearing surface of the lever and an operating member for moving said part into operative position.

9. In a pressing machine, the combination with a horizontal pressing surface, of an arm mounted to operate in a vertical plane, an iron having a shaft with a universal bearing on the said arm, a motor mounted separately from said shaft for moving the iron into co-operative relation with the pressing surface and motor controlling devices embodying a lever supported on said arm having a spherical surface formed concentric to the universal shaft bearing, an actuating lever arranged to co-operate with the spherical surface of the said lever and an operating member on the shaft for adjusting the lever.

10. In a pressing machine, the combination with a horizontal pressing surface, of an arm mounted to operate in a vertical plane, an iron having a supporting shaft with a universal bearing on the said arm and provided

- with a handle for manipulating the iron, a fluid pressure motor carried by the arm for moving the iron into coöperative relation with the pressing surface and having a controlling valve thereon, a bell-crank lever on the said arm having a part arranged to operate the motor controlling-valve and having a bearing surface thereon formed concentric with the center of movement of the said shaft, and an actuating member located on the shaft adjacent to the handle and having a portion coöperating with the concentric bearing surface of the bell-crank lever for operating the latter irrespective of the different angular relations of the said arm and shaft.
11. In a pressing machine, the combination with a suitable pressing surface, of an arm arranged to swing parallel to the pressing surface and supporting a yoke-shaped frame thereon, a rocker arm pivoted to the yoke arms of the said frame to swing in angular relation to the pressing surface, an iron carried on the rocker arm and arranged in coöperative relation with the pressing surface, and a motor operating between the said frame and rocker arm for producing pressure between the iron and pressing surface.
12. In a pressing machine, the combination with a horizontal pressing surface, of a frame mounted to swing in a horizontal plane and having a pair of spaced horizontal arms, a rocker arm pivoted between the spaced arms of the frame and arranged to swing in angular relation to the pressing surface, an iron carried at one end of the rocker arm and arranged to coöperate with the pressing surface, and a motor connected to the other end of the rocker arm for tilting the latter to bring the iron into coöperative relation with the pressing surface.
13. In a pressing machine, the combination with a suitable pressing surface, of a frame movable parallel to the pressing surface, and a rocker arm pivoted thereon to swing in angular relation to the pressing surface, an iron carried by the rocker arm and arranged to coöperate with the pressing surface, a fluid pressure cylinder having a piston operating therein, and operating connections between the said frame and rocker arm which are operated on by the piston for producing a relative movement of the frame and rocker arm.
14. In a pressing machine, the combination with a pressing surface, of a frame arranged above the pressing surface, and a rocker arm pivoted thereon and arranged to swing in angular relation to the pressing surface, an iron operated on by the rocker arm, and a motor mounted on the frame for operating the arm embodying a fluid pressure cylinder having a piston operating therein, and a lever connected to the piston and forming an opera-
- tive connection between the frame and rocker arm.
15. In a pressing machine, the combination with a pressing surface, of a frame mounted to swing in a plane parallel to the pressing surface, and a rocker arm pivoted thereon and arranged to swing in angular relation to the pressing surface, an iron operated on by the rocker arm, and a motor for producing relative motion between the frame and arm embodying a fluid pressure cylinder and piston carried by one of the parts, and a lever connected to the piston and having a pivotal bearing on one of its parts and a link connection with the other.
16. In a pressing machine, the combination with a pressing surface, of a supporting arm, and a rocker arm pivoted thereon and arranged to move in angular relation to the pressing surface, an iron operated on by the rocker arm, and a motor for operating the arm embodying a fluid pressure cylinder and its piston mounted on the arm, a lever pivoted on the supporting arm and having one arm thereof attached to the piston, and a link connecting the other arm of the lever and the rocker arm.
17. In a pressing machine, the combination with a pressing surface, of a supporting arm, and a rocker arm carried thereby and arranged to swing in angular relation to the pressing surface, an iron operated on by the rocker arm and arranged to coöperate with the pressing surface, a motor, connections between the said arms actuated by the motor for operating the rocker arm, and a retracting device movable into and out of operative position and normally operating on the motor connections for restoring the motor and arm to normal position.
18. In a pressing machine, the combination with a pressing surface, of a horizontally movable supporting arm mounted over said surface and a rocker arm mounted thereon and arranged to move in angular relation to the pressing surface, an iron carried by the rocker arm arranged to coöperate with the pressing surface and having an operating handle, a motor for tilting the rocker arm relatively to the supporting arm, said motor being carried on one of said arms, a retracting device exerting a force tending to move the rocker arm to carry the iron out of engagement with the pressing surface and means for preventing the operation of the retracting device to permit manual manipulation of the iron in engagement with the pressing surface.
